UNITED STATES PATENT OFFICE.

EDWARD EICKE, OF HOBOKEN, NEW JERSEY.

DESIGN FOR A BASE FOR PLUMES.

SPECIFICATION forming part of Design No. 18,599, dated September 11, 1888.

Application filed June 1, 1888. Serial No. 275,761. Term of patent 7 years.

To all whom it may concern:

Be it known that I, EDWARD EICKE, of the city of Hoboken, Hudson county, and State of New Jersey, have invented and produced a new and original Design for the Base of Plumes, of which the following is a full, clear, and exact specification.

My invention relates to a design for the base of plumes; and the leading feature of the design consists in a spherical extremity surmounted by circular lines in imitation of a corded surface, and cord-like lines represented as capping the said circular lines, arranged in imitation of a rope coil.

Reference is to be had to the accompanying drawing, forming a part of this specification, in which the figure of the drawing is a front elevation of a plume having my design applied.

A is the base of the plume, which is circular in general contour. At the lower end or extremity of the base a series of circular rope-like lines, *a*, are produced of varied length, grouped to represent a spherical body, *B*.

Above the spherical body *B* a series of cord-like lines, *b*, are produced, one line intersecting the other to produce the effect of a ring or coil, and in the space intervening the representation of the spherical body and the ring or coil are a series of circular lines, *d*, in imitation of a corded surface, the said lines *d* being of greatest length near the coil or ring and shortened as they approach the sphere, whereby a conical or tapering effect is obtained.

I claim—

The design for the base of a plume herein shown and described, consisting of a series of rope-like lines at the extremity representing a spherical body, *B*, a series of circular lines, *d*, of various lengths above the spherical body in imitation of a conical corded surface, and a series of intersecting cord-like lines, *b*, above the corded surface in imitation of a ring or coil.

EDWARD EICKE.
